INVENTOR

UNITED STATES PATENT OFFICE

RUPERT BERNARD NORRIS, OF TULSA, OKLAHOMA, ASSIGNOR TO W. C. NORRIS, OF
TULSA COUNTY, OKLAHOMA

OIL-WELL PUMPING JACK

Application filed April 5, 1929. Serial No. 352,835.

My invention relates to oil well pumping jacks and has for its object to provide a straight lift on the polished rod.

With the above and other objects in view 5 which will appear as the description proceeds, my invention consists in the novel features hereinafter set forth in detail, illustrated in the accompanying drawings, and more particularly pointed out in the appended claims.

Referring to the drawings, in which numerals of like character designate similar parts thruout the several views:

Fig. 1 is a view in side elevation, of a 15 conventional pumping jack of the type having a stationary standard upon which the pumping beam is mounted, with the apparatus constituting the invention in place and showing the movement of the pumping beam.

Fig. 2 is an enlarged detailed view in side elevation, showing portions of the pumping beam and standard, and the said apparatus.

Fig. 3 is an enlarged detailed view in front elevation of the apparatus as shown in Fig. 2.

Fig. 4 is an enlarged top plan view of said apparatus as shown in Fig. 2.

Fig. 5 is a view of the roller cam gudgeons integral with a spacing and holding member for the pumping beam, "A" being a front view 30 and "B" a side view thereof.

1 represents generally the well, and 2 the polished rod attached in the usual manner to a conventional pumping beam 3 made of channel irons suitably spaced and held, which 35 point of attachment constitutes the weight bearing point of the pumping beam. The pumping beam 3 is mounted on a stationary standard represented generally by 4, which stationary standard is shown in the drawings

40 in its conventional construction composed of two channel irons 5 suitably spaced and held in the usual manner. The stationary standard 4 is mounted on any suitable foundation such as a base 6 on which base is also mounted 45 the pumping V or jack proper 7 with a pitman 8 connecting the V 7 with the pumping beam 3. All of the above members are parts of and are arranged in the usual manner in the conventional type of pumping jack as 50 aforesaid.

9 represents an integral part of said stationary standard 4, the same being a cross-arm rigidly attached to the upright portion of the standard, and in its preferred form as shown in the drawings consists of two 55 channel irons 10 arranged longitudinally of the pumping beam 3 with the channels facing each other and spaced apart and held in any suitable manner, such as by bolts and bar 11. Said stationary standard may be constructed in any other suitable manner to hold the pumping beam and apparatus which is the subject matter of the invention.

12 represents a link pivotally attached to the standard 4, the preferred construction placing the point of attachment on a cross-arm as shown and mentioned, in any suitable manner as by bolts 13 having a common axis. Any other suitable construction permitting the pumping beam to oscillate thru 70 its desired course may be used. The link 12 is also pivotally connected to the pumping beam 3 in any suitable manner such as by being mounted on a gudgeon 14 which gudgeon is shown as affixed to or part of a member 15 used to space and hold the channel iron members of the pumping beam 3, said member 15 being similar to the member shown in Fig. 5.

On the pumping beam 3 and located between the pivotal bearing 14 and the weight bearing point of said pumping beam is a roller cam 16 the axis of which constitutes the fulcrum point of the pumping beam. The roller cam 16 is mounted on a member 17 which member also acts as a spacer for the channel irons of the pumping beam, and on which member 17 are gudgeons 18 upon which the roller cam is mounted.

On the standard 4 is a cam track or cam tracks the number of which depend upon the number of cams used. In the drawings is shown a preferred construction of a cross arm 9 composed of two channel irons, and in this arrangement the inner surface 19 of the top 95 flange of the channel irons 10 constitute the cam track, and that in this construction it is obvious that the cross arm is integral with the standard 4 and that to all intents and purposes the cam track is on said standard 4.

When the weight is on the pumping beam the roller cam 16 engages the cam track 19 as the force is exerted upwardly on the cam. The flange 20 on the roller cam 16 assists in 5 keeping the cam on its track. The sides or webs of the channels 10 and the lower flange of said channels, constitute further means of retaining the roller cam on the cam track.

It is evident that a number of different 10 constructions may be used in the arrangement of supports, links or levers, cams and cam tracks, and I do not desire to be limited to the particular construction shown.

The position of the axis of the link 12 with 15 relation to the axis of the cam 16 and to the weight bearing point of the pumping beam 3, and the length of the link 12, are predetermined, so that the arc prescribed by the connecting point of said link 12 and said pumping beam 3 correlates with the arc prescribed by the weight bearing point of said pumping beam 3 to cause said point to move in a straight line thruout the course of its stroke. The link 12 restricts the movement of the 20 pumping beam 3 and actuates it to a movement as above explained.

In operation the pumping beam 3 is oscillated in the usual manner thru pitman 8. With the oscillation of the pumping beam, 25 the link 12 works thru a predetermined arc causing the pumping beam to move longitudinally on the roller cam 16, with the result that the fulcrum point of the pumping beam is changed thruout the course of the stroke, 30 causing the polished rod 2 to travel in a straight line.

Having thus fully disclosed my invention, what I claim and desire to secure by Letters Patent is:

40 1. A pumping jack for pumping an oil well, comprising a pumping beam mounted 105 on a stationary standard, means of oscillating said beam and means of connecting a polished rod to said pumping beam at its weight bearing point; a stationary cam track on said stationary standard with the cam track longitudinally disposed with said pumping beam; a link pivotally connected to said stationary standard, and with said link also 110 pivotally connected to said pumping beam, said link being of a predetermined length and having its axis at a predetermined point with reference to the fulcrum point of said pumping beam to correlate the arc prescribed by 115 the point of its connection on the said pumping beam with the predetermined arc prescribed by the weight bearing point of said pumping beam to cause the last named point to travel in a substantially straight line when 120 said pumping beam is oscillated; a roller cam attached to said pumping beam at a point thereon between said link connection thereto and the weight bearing point thereof, and with said roller cam engaging said cam track 125 and free to move thereon and constituting the 130

fulcrum of said pumping beam; and means of retaining said roller cam on said cam track.

2. A pumping jack for pumping an oil well as claimed in claim 1; wherein said cam track consists of the inner surface of the upper flange of two channel irons rigidly attached to the upright portion of said stationary standard and suitably spaced and held parallel to each other with the channels facing each other; and wherein the aforesaid roller cam consists of two separate rollers suitably mounted on said pumping beam and having a common axis and rotatable thereon and working between the said channel irons and held therein.

80 In testimony whereof I affix my signature.
R. BERNARD NORRIS.
